CENTRIFUGAL CASTING MACHINE

Adolph G. Anderson and James I. Kibbe, Muskegon, Mich., assignors to Campbell, Wyant & Cannon Foundry Company, Muskegon Heights, Mich., a corporation of Michigan

Application May 3, 1937, Serial No. 140,368

12 Claims.

(Cl. 22—65)

This invention relates to a machine for centrifugally casting tubular sleeves. In practice the machine which we have devised is used in casting cylindrical sleeves for use in internal combustion engines, in which the quality of the cast metal must be very high, being of an especially uniform and homogeneous character and capable of being machined to relatively thin cross sections and have substantially perfect inner and outer 10 cylindrical surfaces after machining.

It is a primary object and purpose of the present invention to provide a machine for the use stated, and by means of which the cylindrically cast sleeves may be produced in quantity and with 15 economy, the molds in which the sleeves are cast being quickly introduced into the machine and clamped and held therein, thereupon the molten iron may be poured while the mold is revolved, and after the casting operation has been completed, the mold with the cast sleeve therein removed for the insertion of a succeeding mold.

Many objects and purposes and structure to attain the same are provided, including novel means for securing and clamping the molds in 25 the machine; means for compensating for expansion caused by the high temperature of the molten metal, novel means for air cooling the machine as it is operated, and many other novel constructions and arrangements of parts, all of which 30 will appear and be understood from the following description, taken in connection with the accompanying drawings, in which.

Fig. 1 is an elevation and longitudinal central vertical section through a machine for centrifugally casting elongated cylindrical sleeves in accordance with our invention.

Fig. 2 is an end elevation thereof.

Fig. 3 is a fragmentary section enlarged similar to the section shown at the left in Fig. 1.

Fig. 4 is a fragmentary elevation and section, the section being a horizontal central section through the left-hand portion of the machine shown in Fig. 1, and with the closure member for holding the mold in place swung partially outward; and

Fig. 5 is a transverse vertical section substantially on the plane of lines 5—5 of Figs. 1 and 3, looking in the direction indicated by the arrows.

Like reference characters refer to like parts in 50 the different figures of the drawings.

In the construction of the machine a vertical supporting casting 1 is provided at one side of which is an integral horizontal base 2. An electric motor 3 is mounted upon a carrying table 4 above the supporting casting 1, from which table a vertical post 5 extends downwardly through a sleeve 6 while a pin 7 attached to the table 4 passes through an opening in a flange at the upper end of the sleeve 6 thereby holding the 60 table and the motor thereon from turning move-

ment about the axis of the post 5. The post 5 is equipped with rack teeth at one side meshing with which is a gear 8 carried on a shaft which may be operated to adjust the motor vertically to different positions. The motor shaft has a pulley 9 around which an endless belt 10 passes, the belt also passing around a driven pulley 11 secured at the outer end of the main shaft 12 of the machine. The shafting of the belt is for the purpose of changing the speed of the motor shaft and the belt may be tightened to the desired degree by operation of the shaft carrying the gear 8. A brake 14 is associated with the shaft 12 and is tightened by swinging an operating cam 15 to the left (Fig. 1) through the horizontal movement of a rod 16 connected to the cam member 15 and which is connected to an arm 17 pivotally mounted at one end on the supporting casting 1, and with which is associated a hand lever 18 to apply the brake and stop the shaft 12 at 20 the end of a casting operation.

The shaft extends through and is mounted in suitable bearings 19 and 20 carried by the supporting casting. At its end and extending over the table 2 a mold receiving and holding housing is positioned, preferably cast integral with the shaft 12. Such housing is of cylindrical form, as indicated at 21 (Fig. 4), and has three spaced apart continuous annular ribs 22, 23, and 24, the first of which is intermediate the ends of the cylinder, the second at the open end and the third adjacent the end where it joins with the shaft 12 (see Fig. 3). Longitudinal radially extended and spaced apart vanes 25 extend between and are integrally connected with said annular ribs. 35 An end 27 to the cylindrical housing integrally joins the walls of said housing with the shaft 12 and through this end a plurality of openings 28 are made for air passage. It is apparent that the cylindrical mold holding and carrying member 21 is rotatable with the shaft 12.

A cylindrical cover 30 of suitable thin metal is located around the mold carrying housing described, being connected at one end portion to a ring 31 which in turn is bolted to the supporting casting 1. At its opposite end a substantially continuous annular trough member 32 is located to which a similar ring of angle iron cross section 33 is bolted at one flange, the other flange having a fixed connection to the outer end of the cover 30. This member 32 rests upon the outer portion of the base 2. At its upper side it has a hollow branch 34 which forms an outlet for air which circulates within the enclosed cover 30 during the operation of the machine, the air being drawn through suitable openings, as indicated at 31a in Fig. 3 made near the inner end of the cover 30.

At the open end of the housing 21 a ring 35 is bolted and has a horizontally projecting an-

5 nular flange at the outer side of which a plurality of screw threads 36 are cut, said threads preferably being square threads, though not necessarily so. The inner side of the ring 35 is provided with a conical surface 37 which tapers inwardly as shown.

10 The drive shaft 12 is hollow extending nearly through which is a rod or shaft 38. As shown in Fig. 1, the right-hand end of the shaft bears against one end of a coiled compression spring 39 which is disposed within the hollow drive shaft 12, the opposite end of the spring bearing against an adjusting screw 40 which extends through a screw cap 41 threaded onto the end of the drive 15 shaft 12, an adjusting and locking nut being screwed onto the outer end of the adjusting screw 40 as shown. It permits the tension of the spring 39 to be adjusted. Said spring has a tendency to move the shaft 38 to the left (Figs. 1 and 3). 20 The longitudinal movement of the rod or shaft 38 is limited by a pin 42 (Fig. 3) mounted on and passing through shaft 12 and entering a recess 43 in the shaft 38, the length of said recess less than the diameter of the pin covering the range of 25 adjustment.

30 Said shaft 38 immediately beyond the closed end 27 of the cylindrical mold housing 21 is provided with a head 44 which has air entrance passages 45 therethrough and which has a cylindrical flange 46 continuously around the same and bearing against the inner sides of the cylindrical mold carrying housing 21. The inner sides of the flange 46 are of conical form, as shown at 47, tapering in the same direction and at substantially the same inclination as the inclined conical surface 37 on the ring 35. The end portion of the rod or shaft 38 to which the head 44 is connected is bored longitudinally for a distance receiving a coiled compression spring 48 therein, 40 and also a rod 49 one end of which bears against said spring. The rod 49 extends outwardly beyond the end of the shaft 38 and has a circular plate 50 secured thereto through which are air passages 51. The plate 50 has a vertical outer face as shown. It is evident that the rod 49 and the plate 50 attached thereto may have a limited horizontal movement relative to the spring 48. In Fig. 1 a pin and slot is indicated to limit the extent of such movement.

50 The mold used is formed within a cylindrical tubular flask 52 to the opposite end portions of which are disks 53 and 54, permanently secured, the peripheral edge portions of which are conical surfaces corresponding with conical surfaces 47 and 37, respectively. The mold 55 is of sand located within the flask 52 and has a cylindrical mold cavity into which molten iron may be deposited. The inner end of the mold is thickened radially as shown in Fig. 1 and at the outer end 60 of the mold is a disk-like core 56, the outer vertical face of which lies flush with the end of the flask 52.

65 Horizontal lugs 57 (Figs. 2 and 4) extend from the member 32 on which a drum-like closure member is pivotally mounted to swing about a vertical axis. Said member comprises a cylindrical flange 58 and an outer web 59 in the central portion of which is a circular opening. A ring 60 having screw threads 60a at its inner side is mounted within the flange 58 and connected with the web 59 by bolts 61 which pass through the web and ring. Compression springs 62 surround the bolts between the inner side of the 75 web 59 and said ring 60, the tendency of which

is to move the ring inward until stopped by the nuts on said bolts.

5 A floating member is mounted upon the closure member and within the same, having a cylindrical flange 63 which passes through the central opening in web 59, integral with which flange is a web 64. A continuous annular rib 65 is cast integral with and extends from the drum 63 to which a ring 66 is permanently secured by bolts or screws (Fig. 3). The ring 66 at its outer periphery is 10 provided with square screw threads 67 adapted to coat with the threads 60a on the ring 60. At its inner side the part thereof projecting inwardly from the rib 65 is interiorly threaded, as at 68 with threads of the same size and character as 15 the threads 36 on the ring 35. A ring 69 provided at its outer periphery with continuous gear teeth is secured to and located around the drum 63. A sleeve 70 having a longitudinal passage 71 therethrough is formed integrally with the web 59 20 through which passage a shaft 72 equipped with gear or pinion teeth 73 at its inner end may pass, the teeth 73 meshing with the gear teeth on the ring 69, whereby the floating member may be rotated about its horizontal axis. At the inner edge 25 of the flange 58 of the drum closure member a locating plug 74 is mounted (Fig. 4) adapted to enter a guide recess 75 in the member 32 when the closure member is swung to closed position. A bracket 76 is connected with said flange 58, on 30 which is mounted a pivoted lever latch 77 for releasably engaging with a keeper 78 on the member 32 as shown in Fig. 4 to clamp the closure member in the closed position shown in Figs. 1 and 3. The motor may be controlled by switch 35 buttons such as shown at 79 on the outlet at 84. The core 56 and the web 64 of the floating member described have central openings 80 for entrance of molten iron into the mold.

40 Assuming the parts to be in the position shown in Fig. 4, the floating member has been operated so that it is at its outermost position, and the ring 66 is in screw threaded engagement with the ring 60. The closure member may be swung to wide open position, and a mold with its surrounding flask, consisting of the sand mold 55, the flask 52 and the members 53 and 54 at its ends inserted within the housing 21. The member 53 engaging flange 46 will serve to centrally locate the inner part of the mold and together with the inner end of the mold bears against the plate 50, while the forward member 54 at its conical peripheral edges engages with the conical surface at 37. Core 56 is placed in the outer end of the flask and the closure member is then swung to closed position and latched. The shaft 72 is inserted through the passage 71 and the pinion 73 engaged with the gear teeth of ring 69. Then by rotating the ring in the proper direction the threads 68 will connect with the threads 36 and 45 the floating member be moved horizontally to the position shown in Fig. 1 or 3, and push the mold and surrounding flask ahead of it until the outer peripheral conical surface of the member 54 is 50 brought tightly into engagement with the conical surfaces 37. The plate 50 with the connecting rod 49 will be moved to compress the spring 48 and, if necessary, the head 44 and the shaft 38 with its connecting member moved with a resultant compression of the spring 39.

55 With the parts in this position or as shown in Figs. 1 and 3, the mold is then ready to receive molten iron.

60 The motor is started in operation driving the shaft 12 and the connected parts at high speed 75

of rotation about a horizontal axis. The floating member has a bearing in the opening in the web at 59, and rotates with the cylindrical housing 21. The molten iron is poured through the openings 80 into the mold and the rotation is sufficiently high that the molten iron, through centrifugal action, spreads evenly over the inner sides of the mold 55; and with loss of heat the molten iron solidifies, producing a cylindrical sleeve.

10 The switch controlled by the button at 79 is operated to interrupt the current to the motor and the brake at 14 applied to stop rotation by manual operation of the lever 18 (Fig. 2). The shaft 72 is again inserted but is then rotated in the opposite direction to disconnect ring 66 from the member 35 and reconnect it with the ring 68 as in Fig. 4. Thereupon, the latch 77 may be released from the keeper 78, the closure swung to open position and the flask, mold therein and the sleeve cast within the mold removed from the machine. The succeeding operation is a repetition of what has been described, and the operation may be repeated as many times as desired for the production of a plurality of centrifugally cast elongated sleeves.

15 The rotative speed of the shaft 12 varies with the casting of different diameters of sleeves. It is apparent that the flask 52 may be of a different diameter in which case the radial projection of the members 53 and 54 outwardly from the ends of the flasks will be reduced or increased. For the larger sleeves a rotation of 1200 R. P. M. may be sufficient and for smaller sleeves the rotation may be increased to as high as 3600 R. P. 20 M.; but in any case the rotation must be at a high enough speed that the molten metal is spread out evenly over the entire inner cylindrical surface of the mold.

25 During the rotation, the fin structure comprising the several annular ribs 22, 23, and 24 and the horizontal vanes 25 induce a current of air and also throw the air outward due to centrifugal action, causing a flow of air toward the member 32 to escape through the outlet at 34. Air may pass through the passages 26, 45, and 51 lengthwise of the sleeve which is being cast and heated air likewise passes through the slots 28 outwardly, the inlet of atmospheric temperature air being through the openings 31a.

30 With the structure described the entering of a flask and mold and the removal of the flask, mold and casting therein is rapidly accomplished. The longitudinal expansion of the flask by reason of the great increase in temperature which occurs when the high temperature molten iron is put into the mold is compensated by a yielding longitudinal movement of the rod or shaft 38 with a further compression of the spring 39. The floating mount of the ring 60 on the bolts 61, together with the springs 62 acting on said ring permit yielding of the ring when required as the floating member with the ring 66 attached thereto comes into contact with the ring 35 on closure of the closure member. Rapid production of cast iron alloy sleeves is had. The sleeves, because of the high temperature of the molten iron used, which may be a temperature above 2700° F. are of high quality, the metal is homogeneous throughout without defects, and the free carbon in very finely divided form is thoroughly and homogeneously disseminated through the casting, permitting the casting to be machined accurately and to a relatively thin cross section.

35 The invention is defined in the appended claims

and is to be considered comprehensive of all forms of structure coming within their scope.

We claim:

1. In a machine of the class described, a rotating cylindrical housing adapted to receive an elongated flask enclosing a mold therein, a flask comprising a cylinder and a disk at each end secured thereto, the peripheral edge surfaces thereof being of tapered form, a yielding member at the inner end of said housing including a cup-like end having inner sides with surfaces of conical form corresponding to the peripheral surface of the annular disk at the inner end of the flask, said cylindrical housing at its outer end having an inner conical surface corresponding to the surface at the periphery of the disk at the outer end of the flask, and means for forcing said flask with the mold therein inwardly until the outermost disk at its edges engages with the conical surface at the outer end of the flask thereby centering the flask and holding it firmly in the housing, as specified.

2. In a machine of the class described, an elongated horizontal cylindrical housing open at its outer end, a rotatable hollow shaft to which the opposite end of said housing is connected, a second shaft extending through the hollow shaft, spring means tending to move said second shaft into said housing, a member attached to the end of said second shaft within said housing of cup-like form and having inner tapered sides, a member connected to the outer end of the housing likewise having inner tapered sides, a flask comprising an elongated cylinder and a disk located around each end of the cylinder and secured thereto, said disks having conical peripheral surfaces adapted to coact with the tapered inner sides of said members attached respectively to the second shaft and to the outer end of the housing, a rod extending partially lengthwise of the second shaft, spring means acting thereon tending to move said rod into said housing, a plate having a vertical outer face of an area greater than the area of the end of the flask connected to the rod within said housing, and closure means adapted to be moved into a position to engage with the outer end of said flask and move the same longitudinally against the yielding resistance of said spring means and until the disk at the outer end of the flask comes into snug engagement with the member attached to the outer end of said housing.

3. In a machine of the class described, a cylindrical housing open at its outer end and substantially closed at its inner end, a rotatable shaft to which said housing is connected and from which it horizontally projects, a flask with an elongated cylindrical mold therein located within the housing, means for locating said flask with its axis in substantial coincidence with the axis of said shaft and housing, a cylindrical enclosure around the housing and spaced therefrom, a closure member hinged thereto and adapted to be swung into closing position against the outer end of the flask or to open position, and a manually operable floating member mounted on said closure member and operable to engage with the outer end of the flask and force the same into position, said floating member having an opening therein for the pouring of molten metal into said mold.

4. A construction containing the elements in combination defined in claim 3, combined with yielding means resisting the inward longitudinal movement of the flask, and coacting means on

the housing and the flask for centrally locating the flask in the housing when it has been moved to its innermost position.

5. In a machine of the class described, an elongated cylindrical housing open at one end and substantially closed at the other end, a rotatable shaft connected to the closed end of the housing, said shaft and housing being rotatable about a horizontal axis, an enclosure surrounding the housing and spaced therefrom, a closure member hinged thereto adapted to be releasably held in closed position, a floating member mounted on said closure member for rotation and for bodily movement in a horizontal direction, means for rotating said floating member, interengaging threaded means on the floating member and said housing for connecting the same together on rotation of the floating member in one direction, and interengaging threaded means on the closure member and said floating member for connecting the same together on reverse rotation of the floating member.

6. In a machine of the class described, a rotatably mounted elongated cylindrical housing, means for locating and centralizing an elongated flask with a mold therein in said housing, a surrounding enclosure around the housing, said enclosure at its outer end having an air outlet and said housing having air passing openings for circulation of air on rotation of the housing and for forcing the same outwardly through said outlet, there being air entrance openings into the space between said housing and enclosure therefor, a closure member hingedly mounted on said enclosure, means for releasably securing the closure member in closed position at the outer end of the housing, a floating member mounted within said closure member for rotation and for horizontal movement inward or away from said housing, manually operable means for rotating said closure member, an interiorly threaded ring within the closure member, a cylindrical member both interiorly and exteriorly threaded connected to said floating member, and an exteriorly threaded member connected to the outer end of the housing, said member attached to the floating member screwing thereon when rotated in one direction and screwing into the ring carried by the closure member when rotated in the opposite direction.

7. A rotatably mounted cylindrical housing open at its outer end, an exteriorly threaded member secured at the open end of said housing, a cover surrounding the housing and open at its outer end, a closure member hinged to said cover and adapted to be swung to closed position, means for releasably latching the closure member in closed position, an interiorly threaded ring within the closure member, a second ring both exteriorly and interiorly threaded attached to the floating member, and means for manually turning said floating member operable from outside said closure member.

8. In a machine of the class described, a rotatably mounted horizontally located housing adapted to receive a flask with a cylindrical mold therein, means yieldingly resisting the entrance of the flask to extreme inner position therein, said means engaging with the inner end of said flask, a support adjacent the outer end of the housing, a closure member hingedly mounted on said support and adapted to be swung to closed position or to open position, means for releasably

latching the closure member in closed position, a floating member rotatably mounted within said closure member, means on said floating member, means on said closure member and means on said housing whereby said floating member on rotation in one direction connects with the housing and bears against the flask to move it to innermost position to move with the housing on rotation thereof, and upon rotation of the closure member in the opposite direction disengages from the housing and connects with said closure member to swing therewith to open position.

9. An elongated cylindrical flask, a disk connected to and surrounding each end portion of the flask, said disks having conical peripheral surfaces, a mold within the flask, an elongated housing open at one end to receive said flask and mold which may be moved longitudinally into said housing, said housing adjacent opposite ends having conical interior surfaces to engage with said disks on the flask and means for pressing against the outer end of the flask and forcing the outer surfaces of the disks and housing into engagement with each other to thereby centrally locate the flask, said means closing the outer end of the flask and having a molten metal pouring opening therein, and a plurality of annular ribs around said housing having a plurality of longitudinal vanes therebetween.

10. In a machine of the class described, an elongated horizontal rotatably mounted cylindrical housing having an open outer end for entrance of a flask and mold, therein and a plurality of holes through its closed inner end for the passage of air therethrough, a cylindrical flask with mold therein centrally located in said housing, means for closing the inner end of the flask, means adapted to detachably connect with the outer end of the housing to close the outer end of the flask and having a molten metal pouring opening therein, a movably mounted supporting member and means thereon with which said last mentioned means is connected upon disengagement from said housing.

11. A construction containing the elements in combination defined in claim 10, combined with manually operable means for moving said closing means for the outer end of the flask to selectively connect the same either with said supporting member or the outer end portion of the housing.

12. In a machine of the class described, a horizontally positioned rotatably mounted substantially cylindrical housing open at its outer end, a cylindrical flask with a cylindrical mold therein located within said housing and insertable therein at the open end of the housing, yielding means within the housing against which the inner end of said flask engages and which yields and moves upon the application of a predetermined pressure against the outer end of the flask, locating means on the ends of the flask, on the outer end of the housing and on said yielding means for centrally locating the flask and mold within the housing upon the application of said pressure against the outer end of the flask, a detachable closure for the outer end of the housing screw connectable thereto, and means for manually rotating said closure, said closure member having a molten metal passing opening therethrough for pouring molten metal into said mold.

ADOLPH G. ANDERSON.
JAMES I. KIBBE.
